UNITED STATES PATENT OFFICE.

GEORGE WALTER ESAU, OF MILWAUKEE, WISCONSIN.

DESK CALENDAR.

Application filed October 27, 1924. Serial No. 746,033.

My invention relates to desk calendars, and more specifically, to an improved mechanically operated desk calendar.

One object of the invention is to provide a mechanically operated desk calendar of attractive appearance with indicia of sufficient size to make it a satisfactory calendar, as well as a mechanical toy.

Another object is to provide for regular savings by requiring the deposit of a coin each day to bring the calendar up to date.

One of the primary difficulties in accomplishing the above object is in the provision and proper actuation of separate indicating elements for the units and tens digits of the number indicating the date of the month, so that upon successive actuation, the indication will progress to 31 and change to 1 on the next actuation. If the indicia are to be large enough to be easily seen and read at a glance, so that the device is really a calendar, it is obviously impracticable to have 31 numbers on a single indicating element. This is apparent when it is considered that if the numerals are to be an inch high, the diameter of the single rotary indicating element carrying 31 numbers would need to be substantially one foot.

Another object of the invention is, therefore, to provide a transmission between two indicating wheels, such that the indication will increase by one upon each actuation up to 31 and on the next actuation return, not to zero, but to one.

Another object is to provide means for suitably indicating the months, in connection with the above mentioned means for indicating the day of the month.

Further objects and advantages of my invention will become apparent as the description proceeds.

In the accompanying drawings:

Fig. 1 is a front elevation of an illustrative device embodying my invention, and

Fig. 2 is a central vertical section through the casing and transmission, the indicating wheels being broken away to show the construction more clearly.

Fig. 3 is a section on line 3—3, of Fig. 2, Figs. 4 and 5 are sections on lines 4—4 and 5—5 of Fig. 2; and

Fig. 6 is a section on line 4—4 looking in the other direction.

Fig. 7 is a detail section on line 7—7 of Fig. 5.

In the embodiment of my invention selected for illustration, the entire casing 10 is preferably formed of a single sheet metal stamping. Suitable apertures are provided at 12 for mounting a transparent window, 60 and at 14 for the admission of a coin, and the bottom of the casing is closed by a plate 16 provided with a door 18, preferably fastened in closed position by a spring catch 20.

The main pintle or shaft 22 extends longitudinally from end to end and is riveted over outside the ends of the casing 10. The tens indicator 24 is carried on a sleeve 26 rotatable on shaft 22 and carrying at its extreme ends gear elements 28 and 30. The 70 units indicator 32 is mounted on a sleeve 34 rotatable on sleeve 26 and carrying a gear element 36 at its outer end. The months indicator 38 may be similarly mounted, but in this instance, the use of a sleeve is not necessary, and I have illustrated it as mounted directly on sleeve 26. It carries a gear element 40 at its outer end. The primary drive means for these wheels comprises a plate 42 of the same thickness as the coin to be employed, and having a plurality of serrations 44, thirty-one in number, adapted to be successively engaged by successive coins to be rotated thereby one step at a time. Side plates 46 and 48 are suitably attached 85 to plate 42 and extend radially beyond the same to define a slot for receiving the coin. Two internal ring gears 50 and 52 are carried by plate 48, gear 50 lying in the plane of gear 36 and gear 52 in the plane of gear 30.

The interconnections between the parts for operating them in the proper sequence will now be described. Each time a coin is inserted through aperture 14, it is held in 95 operative engagement with one of the serrations 44 by means of an inturned lip 54 on the casing, a sufficient length of time to move plate 42 substantially one serration. A suitable spring 54' is provided, having a 100 curved end to engage between the serrations and insure a step by step movement. Teeth of gear 50 mesh with an intermediate pinion 56, which pinion drives pinion 36 and the units indicator 32. As gear 50 is a thirty-one toothed gear and pinion 36 has ten teeth, each movement of plate 42 will rotate the unit indicator 32 one-tenth of the revolution. This indicator carries the series of indicia 1, 2, 3, 4, 5, 6, 7, 8, 9, 0. 110

The tens indicator 24 is driven through pinion 30 and intermediate pinion 58 from ring gear 52, which has only four teeth spaced apart by intervals equal to ten, ten, nine and two actuations of plate 42. The indicia carried by indicator 24 comprise a series 1, 2, 3, blank, repeated three times, dividing the circle into twelve equal parts, and pinion 30 has twelve teeth. The parts are so assembled that tooth 60 will move indicator 24 from 3 to blank, after nine more actuations tooth 62 will move it from blank to 1, after ten more actuations tooth 64 will move it from 1 to 2, after ten more actuations tooth 66 will move it from 2 to 3, and after two more actuations tooth 60 will return it to blank.

This provides for moving indicators 24 and 32 to indicate a continuous series from 1 to 31. To change the indication from 31 to 1 on the next actuation, it is necessary to move indicator 24 but not indicator 32. For this purpose, two teeth are cut away on gear 50 as indicated at 68 in Fig. 5. In the position shown in this figure, tooth 66 has just moved indicator 24 to 3, and indicator 32 reads 0. Upon the next actuation, indicator 25 will remain stationary, and the last tooth before space 68 will move indicator 32 from 0 to 1. On the next actuation, tooth 60 will move indicator 24 from 3 to blank, but the movement of gear 50 will merely carry space 68 across, so that the first tooth beyond it will engage pinion 56 on the next actuation. In this way, by driving both indicators 24 and 32 direct from plate 42 by independent transmissions, the correct sequence is obtained.

Gear 28 on the other end of sleeve 26 has three equidistantly spaced teeth, which mesh with an intermediate pinion 70 pivoted on the wall of casing 10. Pinion 70 is of double width, and is continuously in mesh with pinion 40. It will be apparent that each time indicator 24 completes one-third of a revolution, one of the teeth of pinion 28 will move the months indicator 38 one step. Suitable stop springs 72 are employed to prevent accidental displacement of each of the indicators, and assure step by step movement. I prefer to mount these springs on the end walls of casing 10, and to have them engage the intermediate drive pinion in each instance. The indicia carried by all three indicators should preferably be of the same size, and the indicia on indicator 32 will be spaced further apart than on the other indicators. It should be noted that no indicator moves less than one-twelfth of a revolution on any actuation, and that the side of the indicia that can be placed on an indicator of given size is thus a trifle more than two and one-half times what could be employed if thirty-one indicia were to be carried on a single indicator.

Without further elaboration, the foregoing will so fully explain the gist of my invention, that others may, by applying current knowledge, readily adapt the same, for use under various conditions of service. It will for instance be obvious, that the shape of the casing may be varied according to any one of a large number of pleasing designs, and that the sloping sides illustrated in the embodiment shown in the drawings may be corrugated to retain pens and pencils, if desired. These and many other modifications and alterations may readily be made without eliminating certain features which may properly be said to constitute the essential items of novelty involved, which items are intended to be defined and secured to me by the following claims.

I claim as follows:

1. In a calendar of the class described, the combination of a housing, a shaft extending through and secured to the housing walls, a sleeve rotatable on said shaft, a tens date wheel secured on said sleeve to rotate therewith, a units date wheel journaled on said sleeve to rotate thereon, an actuating member concentric with said shaft and adapted to rotate independently thereof and of said units wheel, said actuating member having 31 teeth thereon, means for inserting coins into said housing and against said actuating member to advance such member one tooth for each coin inserted, a driving gear connected with said actuating member, a pinion secured to said units wheel, a transmission gear between said driving gear and said pinion, a second driving gear connected with said actuating member, a pinion secured on said sleeve, and a transmission gear between said second driving gear and said sleeve pinion, said units wheel having ten date indications 1 to 0 thereon, said tens wheel having the indication series 1, 2, 3 and blank three times repeated, said transmission gears being proportioned to cause one step advancements of said wheels for each one tooth advancement of said actuating member.

2. In a calendar of the class described, the combination of a housing, a shaft secured in said housing, a sleeve journaled thereon, a tens date wheel secured on said sleeve to rotate therewith, a units date wheel journaled on said sleeve to rotate thereon, an actuating member concentric with said shaft and rotatable relative thereto and to said wheels, said actuating member having 31 teeth, a coin slot, means controlled by the insertion of a coin for advancing said actuating member the distance of one tooth, an annular gear secured to said actuating member, a pinion connected with said units wheel, a transmission gear between said annular gear and said pinion, a second annular gear carried by said actuating member,

- a pinion on said sleeve, and a transmission gear between said second annular gear and said sleeve pinion, said annular gears, pinions and transmission gears being proportioned to cause rotation of the date wheels to indicate successive dates when said actuating member is progressively advanced.
3. In a calendar device of the class described, the combination of a housing, a shaft supported in said housing, a sleeve journaled on said shaft, a units wheel journaled on said sleeve to rotate thereon, a tens date wheel secured on said sleeve to rotate therewith, a month wheel journaled on said sleeve to rotate thereon, an actuating member concentric with said shaft and

rotatable relative to said wheels, coin inserting mechanism for said housing, means for causing an inserted coin to effect a 1/31 part of a complete revolution of said actuating member, and a transmission train between said actuating member and each of said wheels, said trains being proportioned to cause said wheels to be set up to indicate the date as said actuating member is progressively advanced by the insertion of coins.

In witness whereof, I hereunto subscribe my name this 22nd day of October A. D., 1924.

GEORGE W. ESAU.
